US00D735343S

(12) **United States Design Patent**
Dorsey et al.(10) **Patent No.:** **US D735,343 S**
(45) **Date of Patent:** **** Jul. 28, 2015**(54) **CONSOLE**(75) Inventors: **Michael C. Dorsey**, Edwardsville, IL (US); **David Rork Swisher**, St. Charles, MO (US)4,919,651 A 4/1990 Doane
4,996,975 A 3/1991 Nakamura
5,025,778 A 6/1991 Silverstein et al.
5,059,182 A 10/1991 Laing
5,131,380 A 7/1992 Heller et al.(73) Assignee: **Covidien LP**, Mansfield, MA (US)

(Continued)

(**) Term: **14 Years**

FOREIGN PATENT DOCUMENTS

EP 0299240 A2 1/1989
EP 1707102 A1 10/2006(21) Appl. No.: **29/431,433**

4,782,819 A	11/1988	Adair
4,809,680 A	3/1989	Yabe
4,846,153 A	7/1989	Berci

FIG. 1 is a front perspective view of a console;
 FIG. 2 is a rear perspective view of the console of FIG. 1 showing a stowed stand and feet in phantom;
 FIG. 3 is a front view of the console of FIG. 1;
 FIG. 4 is a right side view of the console of FIG. 1;
 FIG. 5 is a top plan view of the console of FIG. 1;
 FIG. 6 is a rear view of the console of FIG. 1;
 FIG. 7 is a left side view of the console of FIG. 1; and,
 FIG. 8 is a bottom plan view of the console of FIG. 1.
 The elements shown in phantom form no part of the claimed design.
